UNITED STATES PATENT OFFICE.

CHARLES H. BOECK, OF MILWAUKEE, WISCONSIN.

OIL-STOVE.

SPECIFICATION forming part of Letters Patent No. 407,569, dated July 23, 1889.

Application filed April 6, 1888. Serial No. 269,851. (No model.)

To all whom it may concern:

Be it known that I, CHARLES H. BOECK, of Milwaukee, in the county of Milwaukee, and in the State of Wisconsin, have invented certain new and useful Improvements in Oil-Stoves; and I do hereby declare that the following is a full, clear, and exact description thereof.

My invention relates to oil or lamp stoves, and will be fully described hereinafter.

In the drawings, Figure 1 is a central longitudinal section of my improved stove. Fig. 2 is a detached view of the wick-holder partly sprung open. Fig. 3 is an enlarged view of the same closed, but partly broken away to show the interior, and partly in section on the line 3 3 of Fig. 4. Fig. 4 is a horizontal section on line 4 4 of Fig. 3. Fig. 5 is a detail section on line 5 5 of Fig. 3. Fig. 6 is a section on line 6 6 of Fig. 1, with the burner and reservoir removed.

The frame of my improved stove consists of corner pieces A, terminating in suitable legs connected by side pieces and by the sides and bottom of the heat-chamber B. The front part of latter has a flange a to receive the rim b or base of the deflector-frame C. The deflector-plate D is suspended by a rod c from the top of the frame C. The upper end of rod c is adjustably secured to its support, so that the height of the deflector-plate may be easily regulated.

E is the draft-chamber, which is suspended from the flange a, and this chamber is provided with a door f in front to permit the removal of the burner or to give access to the flame.

The burner F and reservoir G are connected by a pipe g, and the side pieces H of the frame are formed each with a flange h to receive the reservoir, which is shoved in between the side pieces from the front, and a nest i for the bottom of the burner is hung between the front ends of the side pieces by stays i'. The front of the nest i is open to admit of the withdrawal of the burner, but its rear is formed with a guard j to prevent the burner from going in too far.

The nest and guard are dropped to a plane lower than that of the flange h to permit the withdrawal of the reservoir.

My burner consists of the usual annular cup F, which is suspended from the reservoir by stays M, and the wick-tube, which fits in the cup F, consists of a perforated inner wall m, through which the oil passes to the wick, 55 and a split outer wall N for clamping the wick when it is properly adjusted in the cup. One of the meeting edges of the wall N is formed with two short tubes p and the other with a long tube q, which latter fits between 60 the short tubes when the edges of the wall are clamped together, so that the tubes register to receive a pin s, the top of which is formed with a stop t, that extends over the top of the lifting-rack u of the wall. 65

The outer wall of the cup F is formed with an internal channel n, which embraces the joint p q and the rack u, as well as a pinion L, and the shaft P of the pinion L has its bearing in a sleeve R, that is secured to the outer 70 face of the channel n.

Gas is prevented from flowing up through channel n by the stop t. Between the walls m and N is confined an ordinary wick T, of less height than the walls of the tube, and above 75 this is arranged a strip of asbestos or other non-combustible but porous material U, and these are clamped in place between the walls m and N. By turning the pinion the split wall or tube is worked vertically, thereby raising or lowering the wick, as the case may be. 80

Having thus fully described my invention, what I claim as new, and desire to secure by Letters Patent is—

1. In an oil-stove, the combination, with 85 the frame, of flanges h, projecting inwardly from the sides of the frame, the nest i at the front of the stove supported by the said flanges, and a removable reservoir and burner arranged, respectively, on the flanges and 90 nest and secured to and communicating with each other, substantially as described.

2. The combination, in a burner, of a continuous inner tube and a split outer tube, and a sectional wick the upper section of 95 which is of practically incombustible material.

3. In an oil-stove, a burner consisting of the cup F, the wick-tube having a perforated inner wall and a split outer wall, with means 100

for uniting the severed edges, the wick between the walls, a rack *u* on the outer wall of the wick-tube, and a pinion meshing therewith operated from the outside of the cup, 5 substantially as described.

In testimony that I claim the foregoing I have hereunto set my hand, at Milwaukee, in

the county of Milwaukee and State of Wisconsin, in the presence of two witnesses.

CHARLES H. BOECK.
